UNITED STATES PATENT OFFICE.

AUGUST C. G. CALEB AND JOHN B. COUTURE, OF CLEVELAND, OHIO.

SOIL-PIPE-CUTTING MACHINE.

SPECIFICATION forming part of Letters Patent No. 430,727, dated June 24, 1890.

Application filed March 31, 1890. Serial No. 345,961. (No model.)

To all whom it may concern:

Be it known that we, AUGUST C. G. CALEB and JOHN B. COUTURE, both citizens of the United States, residing at Cleveland, in the 5 county of Cuyahoga and State of Ohio, have invented a new and useful Soil-Pipe-Cutting Machine, of which the following is a specification.

This invention relates to a machine for 10 cutting pipe of the sizes usually used as soil-pipe by plumbers, and has for its object to greatly facilitate, cheapen, and improve the work of cutting such pipes, which heretofore has generally been done by means of the 15 hammer and chisel; and the invention consists in the peculiar construction and combinations of mechanism, substantially as hereinafter described, and pointed out in the claims.

20 In the accompanying drawings, Figure 1 is a side elevation of our machine. Fig. 2 is an end elevation, and Fig. 3 is a top or plan view of the same. Fig. 4 is an elevation of the machine having the vise removed for showing 25 the cutting mechanism.

A represents a half-circle guide-frame firmly attached to a suitable bed-plate or frame B.

20 C represents a heavy ring fixed to turn in said guide-frame A, being held by clips c, 30 through which the ring slides. Within this ring is arranged the cutting mechanism, consisting as follows:

D are two right and left hand screws, supported at each end in suitable bearings d 35 d in the ring, and at their middle part by arms d² d². On the upper ends of each of said screws is provided a pinion e e, and in a suitable bearing e² is placed a shaft F, carrying a gear E, meshing with said pinions, and de- 40 signed as a means for turning said screws.

G G are two cross-bars having screw-threaded nuts g g on each end, playing on the said screws D D on each side of their middle part.

45 H H are also cross-bars having non-screw-threaded nuts or eyes h h on each end and also sliding on said screws D D. The bars H H are connected to the bars G G by means of springs s s, and carry cutting-tools T T, consisting of curved saw-blades adjustably fastened in slots in the middle part of said bars.

At a suitable distance from said cutting mechanism is provided a vise for holding a pipe to be cut. This consists of two posts P P, firmly fixed to the bed-plate or frame B, having a cross-head Q, in the middle of which is a screw-threaded nut q, through which a screw R plays.

N is a movable clamping-jaw having grooved guides n n on each end, which slide 60 on the sides of the posts P P, and is connected by a swivel-joint at its middle part to the lower end of said screw R, by which said jaw is moved up or down. The underside of said jaw is provided with a roughened surface. 65

O is a lower movable or adjustable jaw set in guideways p p on the insides of the two posts P P, the top of which is curved and has a roughened surface. On the inside of the posts are provided rack-teeth V V, and to the 70 sides of the jaw O are fixed pawls W W, by which said jaw may be adjustably set to accommodate the vise to different sizes of pipe. The one crank may be used for turning the shaft F or screw R. 75

The method of using this machine is as follows: The pipe to be cut is clamped in the vise, as seen in Figs. 1 and 3, with the end between the cutters. The cutters are run together onto the pipe by rotating the screws D 80 by means of the shaft F and gear E. Now, by turning the ring C in the guide-frame B, by using the shaft F as a handle, giving the ring half-revolutions, and as fast as the cutters enter, the shaft F is turned for drawing the 85 cutters inward. In this manner the pipe is quickly and smoothly cut off.

Having described our invention, we claim—

1. In a machine for cutting pipe, the combination of a guide-frame A, supported on a 90 suitable bed or frame B, a ring C, fixed to turn in said guide-frame and having the right and left hand screws D D journaled therein, a shaft F, gear E, and pinions e e, for turning said screws, the cross-bars G G, having nuts 95 g g playing on said screws, the cross-bars H H, also having eyes sliding on said screws D D and attached to the bars G G by springs s s, and having the cutting-blades T T adjustably attached, all constructed to operate substantially as and for the purpose specified. 100

2. In combination with the pipe-cutting

mechanism hereinbefore described, the vise for holding the pipe, consisting of posts P P, standing on bed B, cross-head Q, provided with nut q, and screw R, playing therethrough, 5 the clamping-jaw N, attached by swivel-joint to said screw and having guides n n, the adjustable jaw O, fixed in guides p p on posts P P, and having pawls W W, engaging with

racks V V on said posts, all constructed and arranged to operate substantially as and for 10 the purpose set forth.

AUGUST C. G. CALEB.
JOHN B. COUTURE.
